UNITED STATES PATENT OFFICE.

JOHN RICHARDS, OF COLUMBUS, OHIO.

IMPROVEMENT IN LUBRICATORS FOR SCROLL-SAW STOCKS.

Specification forming part of Letters Patent No. 36,729, dated October 21, 1862.

To all whom it may concern:

Be it known that I, JOHN RICHARDS, of Columbus, in the county of Franklin and State of Ohio, have invented a new and useful Improvement in Lubricators for Scroll-Saw Stocks; and I do hereby declare that the following is a full, clear, and exact description of the same, reference being had to the accompanying drawings, forming part of this specification, in which—

Figure 1 is a partial side view and partial vertical section of a scroll-saw stock-guide and my improved lubricator. Fig. 2 is a full side elevation of the same. Fig. 3 is a horizontal section of the same.

Similar letters of reference in the several figures indicate corresponding parts.

The nature of my invention consists in the combination, with two separated bearing and guide boxes, of an intermediate tubular lubricating device. The said device, having its bore or chamber made with a greater diameter than the bore of the guide-boxes, so that while the saw-stock is necessarily fitted snugly within the boxes, a space exists between the saw-stock and the tubular lubricating device, said space serving to contain cotton-waste and lubricating-fluid.

To enable others skilled in the art to make and use my invention, I will proceed to describe the same with reference to the drawings.

A represents a casting of T form in its horizontal section, and having its web portion *a* hollowing or of yoke shape, as at *b*. This casting is formed with an upper bearing and guide box, *c*, and a similar lower box, *d*, said boxes being half in the casting, and half in screw-plates *e e*, as represented. The casting A bolts firmly to an upright pillar of a scroll-saw table or frame and occupies a position below said table.

B is a light metal tube with an oil-induction spout, C, leading into it. The diameter of this tube, internally, is considerably greater than the diameter of the interior of the boxes *c d*. The tube B C is arranged between the two boxes *c d*, and is supplied with a lining of cotton-waste, *f*, or other material which will absorb and retain oil or lubricating-fluid when the same is poured through the spout C into the tube B, as illustrated.

D is the saw-stock; E, the saw, and F the pitman. The stock is made many sided and of a size to just snugly fit and slide up and down in the boxes *c d*. By being many sided,

which is the shape of the boxes, it cannot turn after being set, and by being fitted snugly to the boxes it cannot "wabble" or saw untrue. The size of the stock is equal from end to end, and, therefore, that portion which comes between the boxes *c d* does not come in contact with the lubricating-tube B, but plays through the lining *f* formed of cotton-waste saturated with oil or lubricating-fluid.

When the stock is adjusted to its position, as shown in Figs. 1, 2, and 3, the half-boxes or screw-plates *e e* are screwed in place, as shown.

My invention thus described is designed especially to prevent the heating of the saw-stock and the consequent firing of the mill—a difficulty experienced by myself in the use of the patented mills of my own, dated May 27, 1862. The great speed at which scrollsaws are run, and the necessary close fit of the stock to its bearing and guide boxes, are the cause of the heating and setting fire to the mill. Now, to obviate this dangerous defect, and still not destroy the nice fit between the stock and its guide-boxes, was a matter of much study and contrivance, and the simple and effective plan which I have devised is of as much importance, in one view of the case, as the whole mill, for without it, or its equivalent, the mill is useless for high speeds.

From the drawings it will be evident that most of the dust from the saw falls directly upon the top bearing, and, owing to this, it becomes necessary that a constant and perfect lubrication of the parts be maintained, in order to compensate for the absorption of the oil by the sawdust. Such constant and perfect lubrication is effected by the waste cotton, hemp, or other absorbent material, saturated with oil poured in through the tube C and distributed evenly over the surface of the stock; any undue heating of the stock causing a greater quantity to flow from the absorbent lining of the tube to counteract it.

What I claim as my invention, and desire to secure by Letters Patent, is—

The combination of the bearing and guide-boxes *c d*, intermediate casing, B, and saw-stock, or the equivalent thereof, constructed and operating and arranged substantially in the manner and for the purpose described.

JOHN RICHARDS. [L. S.]
